(57) **CLAIM**

The ornamental design for a floatation device for solar panels, as shown and described.

DESCRIPTION

FIG. 1 illustrates a first perspective view of a floatation device for solar panels.

FIG. 2 illustrates a second perspective view thereof.

FIG. 3 illustrates a first side view thereof.

FIG. 4 illustrates a second side view thereof.

FIG. 5 illustrates a front view thereof.

FIG. 6 illustrates a top view thereof; and,

FIG. 7 illustrates a bottom view thereof.

The broken lines shown represent the portions of the floatation device for solar panels that form no part of the claimed design.
